UNITED STATES PATENT OFFICE.

CHARLES W. GAGE, OF HOMER, NEW YORK.

IMPROVED ATTACHMENT OF THE TOW-LINES OF CANAL-BOATS.

Specification forming part of Letters Patent No. 38,224, dated April 21, 1863.

To all whom it may concern:

Be it known that I, C. W. GAGE, of the town of Homer, and State of New York, have invented certain new and useful improvements in dead-eyes as a safeguard for horses when drawing canal-boats; and I hereby declare that the following is a true and exact description of the same, reference being had to the accompanying drawings, and to the letters of reference marked thereon.

Figure 1 represents a perspective view. Fig. 2 is a plan view of the same inverted.

A and B represent two elevations near opposite ends. The rod C is inserted at its larger end into an opening in A. The rod C is secured in this horizontal opening by a bolt or pin, which passes through the upper jaw of A, through C into the lower jaw of A, the hole in C being large enough to admit of the horizontal motion of the rod C. The end of C next to the shoulder in the opening of A is rounded so that it can pass sufficiently far to the right or left to perform the office assigned it, which is to disengage itself from the loop of the cord which passes over it, the opposite end of this cord being the point to which the horses are hitched. The spring-lever d passes through the elevation B in a line with C, and has a head on it the lower part of which extends nearly to the bottom of B. This head is designated by the letter e and has a cavity in it large enough to receive the end of C. The lever d has a shoulder on it at f, (shown by dotted lines,) against which one end of the spiral spring g rests, the other end pressing against the shoulder h, also exhibited in dotted lines. The end of d extends sufficiently far beyond the outside of B to admit of a cord passing through it and reaching to the stern of the

boat, so as to be controlled by the helmsman.

The letter k represents a block, which fits at its base into a mortise cut in the body of the machine between A and B. The top of k when in position supports the rod C, and the back of it rests against e. k is confined in its position by an iron bolt, its base resting upon the opening j, as seen in Fig. 2. The pressure of j upon the block k and the corresponding pressure of k upon C prevents the cord from slipping off and thus disengaging the horses unseasonably.

The mode of operating my machine is as follows—viz: It is first secured firmly to the prow of the boat, the elevation A being foremost, and the horses hitched to the cord looped around C. The rope attached to the end of lever d extends to the helmsman, who, when he desires to disengage the horses, pulls the lever D back, relieves C from the socket in e, and the cord, by its oblique pressure upon C, draws it around, and the cord slips off. If, on the other hand, the horses should fall behind the boat and are in danger of being dragged into the canal, the cord is thrown into a position to force d back at the same time that it presses the block k downward and slips off from the rod C.

Having thus described my invention, what I claim, and desire to secure by Letters Patent, is—

The lever d, the rod C, the block k, and the spring j, the whole arranged in the manner and for the purpose substantially as herein described.

CHARLES W. GAGE.
